(57) **CLAIM**

The ornamental design for an electronic device, as shown and described.

DESCRIPTION

FIG. 1 is a front, top perspective view of an electronic device showing our new design;

FIG. 2 is a front, bottom perspective view thereof;

FIG. 3 is a rear, top perspective view thereof;

FIG. 4 is a rear, bottom perspective view thereof;

FIG. 5 is a front view thereof;

FIG. 6 is a rear view thereof;

FIG. 7 is a left side view thereof;

FIG. 8 is a right side view thereof;

FIG. 9 is a bottom view thereof; and,

FIG. 10 is a top view thereof.

The broken lines illustrate structure that forms no part of the claimed design.

The drawings include surface shading that represents contour and not surface ornamentation.
